US00D677517S

(12) **United States Design Patent**
Dichraff et al.

(10) **Patent No.:** **US D677,517 S**
(45) **Date of Patent:** **** Mar. 12, 2013**

(54) **PAN**

(75) Inventors: **Aric Dichraff**, Madison, WI (US); **Craig Stevenson**, Saukville, WI (US); **Erik Johnson**, Middleton, WI (US); **Morad Ghasseian**, Oak Park, IL (US); **William Cesaroni**, Glenview, IL (US); **Jared Fritts**, Forest Park, IL (US); **Christian Baumgarten**, Neunkirchen (DE)
